REFRIGERATION APPARATUS

Regis D. Heitchue, Cranford, N. J., assignor to
Westinghouse Electric Corporation, East Pitts-
burgh, Pa., a corporation of Pennsylvania

Application February 14, 1944, Serial No. 522,247

11 Claims. (Cl. 230—235)

1

My invention relates to refrigerating apparatus, more particularly to the enclosed type of motor-compressor unit forming part of such apparatus.

One object of this invention is to produce an improved motor-compressor unit of the type set forth.

A further object of this invention is to produce an improved motor-compressor unit construction by means of which operational, vertical and horizontal vibrations and vibrations produced by the starting and stopping torque of the motor, are effectively absorbed and the noises incidental to such vibrations are considerably reduced.

A still further object of this invention is to produce an improved motor-compressor unit construction by means of which the assembly of the component parts of the unit within, and the removal of said parts from the shell or casing enclosing the same is facilitated.

These and other objects are effected by my invention as will be apparent from the following description and claims taken in connection with the accompanying drawing, forming a part of this application, in which:

Fig. 1 is a view partly in elevation and partly in section showing a motor-compressor unit embodying my invention;

Fig. 2 is a sectional view on line II—II of Fig. 1; and

Fig. 3 is a fragmentary vertical sectional view showing details of construction.

Referring to the drawings and more particularly to Fig. 1, there is shown a motor-compressor unit comprising a pump or compressor 10 and a motor 12. The motor-compressor unit is enclosed in a shell or casing 14 having a lower or body portion 16 and an upper or cover portion 18. The casing portions 16 and 18 are secured together in fluidtight relation by bolts or the like 20 engaging suitable flanges 22. The motor-compressor unit may be of any desired internal construction and hence is neither shown nor described in detail.

In order to absorb vertical vibration, the motor-compressor unit is supported by a helical compression spring 24 interposed between the bottom of the compressor and the bottom of the casing portion 16. As shown, the spring 24 is confined between a shoulder 26, formed on the exterior of a socket 28, and a collar or the like 30, formed on or carried by the bottom of the unit, or on a head 32 threaded into or otherwise engaging a recess 34 in the bottom of the unit 10. The head 32 may be retained in position by a set screw 36. 55

2

The head 32 carries a pin 38 which extends into the socket 28 to limit the tilting of the compressor unit when the same is subjected to extreme jarring as in transportation or handling.

5 While I have shown and described a specific form of assembly of the spring 24, it is obvious that other means for positioning and confining the supporting spring 24 may be employed.

In order to absorb operational, horizontal or lateral vibration and vibration incident to stopping and starting of the motor, the motor 12, or the upper portion of the motor-compressor unit, is connected to the casing portion 16 by horizontally yielding cushioning means. Such means is

10 preferably in the form of springs disposed tangentially of a circle concentric with the axis of rotation of the motor shaft, together with means for transmitting horizontal or lateral vibrations of said unit to said springs. As shown in Figs. 1 and 2, the preferred form illustrated is provided with two diametrically opposed sets of springs, but, inasmuch as the two sets of springs are identical in structure and function, only one set of springs will be described in detail.

20 From Fig. 1 it will be seen that each of said sets of springs includes two compression springs 40, the outer ends of which are seated in cup washers or the like 42 carried by a bolt 44 which in turn passes through suitable openings in

25 plates 46 and is secured in position by any suitable means 48. The plates 46 are carried by the casing portion 16 and upwardly extend into the cover portion 18. The lateral or horizontal vi-

30brations of the unit are transmitted to the springs 40 by means of a plate 50 interposed between the motor 12 and the springs 40. As shown, the lower portion of the plate 50 is pro-

35 vided with an opening 52 through which the bolt 44 passes and with recesses in the opposite faces thereof which receive and engage the inner ends of the springs 40. The opening 52 is of a greater diameter than the bolt 44. The upper portion of the plate 50 is secured to the motor 12 by one or more bolts 54 threadedly engaging the plate

40 and passing through openings 56 in lugs 58 carried by or formed integrally with the motor 12. The openings 56 in the lugs 58 are elongated so as to permit vertical adjustment of the parts.

The openings 56 may also be wider than the diameter of the bolts 54 thus permitting horizontal adjustment also. In order to adjust the clearance between the motor-compressor unit and the interior of the casing 14, shims 60 may be interposed between the lug 58 and the plate 50. 55

The upper or cover portion 18 of the casing

is provided with an inlet 62 through which refrigerant gas from an evaporator (not shown) is admitted. The refrigerant gas flows through or around the motor 12 to cool the latter and is then sucked into the pump 10 where it is compressed and discharged through a pipe 64 to a condenser (not shown) where the hot compressed refrigerant gas is cooled and liquefied.

Assembly

The compressor 10 is lowered into the casing 16 and the pin 32 is caused to pass through the spring 24 and into the socket 26, as shown in Fig. 1. The motor 12 is then lowered onto the top of the compressor 10, and the flanges 66 of the pump and motor casings are suitably secured together in any well-known manner. The springs 40, washers 42, bolt 44 and plate 50 are then assembled on the plates 46. The plate 50, with or without one or more shims 60, is then secured to the lug 58 by the bolts 54. Vertical adjustment can be obtained by moving the bolts 54 up or down in the elongated slots 56. The cover portion 18 is then lowered onto the motor casing portion 16 and the flanges 22 are secured together by the bolts 20. It is to be noted that the plates 46 extend upwardly from the casing portion 16 and that the spring assembly carried thereby is disposed within the cover portion 18 so that when the cover portion 18 is removed from the lower portion 16, the cushioning means interconnecting the motor 12 to the upper portion of the casing 16 are entirely accessible.

Operation

With the motor-compressor unit mounted as above described, the lower spring 24 yieldably supports the entire weight and serves to absorb vertical vibration. The springs 40 absorb lateral or horizontal vibration and are of such strength as to absorb the full torque of the motor without being fully compressed.

If during shipment or handling the compressor unit is tilted to such an extent as unduly to distort the spring 24, the pin 38 will come into contact with the wall of the socket 26 and provide a rigid stop which will limit the tilting movement of the compressor relative to the casing. Likewise, the opening 52 in the lower end of the plate 50, coacts with the bolt 54 to limit vertical and horizontal movement of the compressor transversely of the bolt 44.

It will thus be seen that I have produced a motor-compressor unit construction in which vertical and horizontal vibrations and the starting and stopping torque of the motor are effectively cushioned or absorbed, thus reducing operational noises and preventing the motor-compressor unit 10 from hitting against the interior of the relatively closely fitting casing. In addition, a motor-compressor unit constructed according to my invention is easily assembled in, or removed from the casing with minimum skill and labor.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In apparatus of the character stated, a casing, a motor-compressor unit disposed vertically

within said casing, resilient means intermediate the bottom of said unit and the bottom of said casing for yieldably supporting said unit and cushioning vertical vibration thereof, and cushioning means compressible tangentially of a circle concentric with the axis of rotation of the motor of said unit and resiliently connecting the upper portion of said unit to an upper portion of said casing for cushioning operational lateral vibration of said unit and the starting and stopping torque of the motor of said unit.

2. The structure recited in claim 1 in which said second-mentioned means includes a plate rigidly carried by said unit and movable relative to said casing, and tangentially-compressible springs carried by said casing and engaging said plate.

3. The structure recited in claim 1 in which said second-mentioned means includes a vertically-disposed plate rigidly carried by said unit and movable vertically and horizontally relative to said casing, tangentially-compressible springs carried by said casing and engaging said plate, and means for limiting the vertical movement of said plate.

4. The structure recited in claim 1 in which said second-mentioned means includes a plurality of vertically-disposed and diametrically-opposed plates carried by said unit and movable relative to said casing, and a plurality of oppositely-disposed, tangentially-compressible springs carried by said casing and engaging opposite sides of each of said plates.

5. In apparatus of the character stated, a casing, a vertically disposed compression spring in the lower portion of said casing, a pump supported by said spring, a motor disposed above said pump for actuating the same, a pair of spaced vertically disposed plates carried by said casing, a horizontally disposed bolt passing through said plates, a vertically disposed arm, means for rigidly and adjustably securing said arm to said motor, there being an aperture in the lower portion of said arm through which said bolt passes, said aperture being larger than the thickness of said bolt, and oppositely disposed, horizontally compressible springs confined between said plates and the opposite sides of the lower end of said arm for yieldingly resisting the horizontal movement of said arm to absorb horizontal vibration and the starting and stopping torque of said motor.

6. In apparatus of the character described, a casing, a spring in the lower portion of said casing, a motor compressor unit supported on said spring, vertically disposed plates carried by said casing, a vertically disposed arm carried by said unit with the lower end of said arm disposed between said plates, and horizontally disposed springs compressible tangentially of a circle concentric with the vertical axis of said unit and engaging said plates and the opposite sides of the lower end of said arm for yieldingly resisting the movement of said arm to absorb horizontal vibration and the starting and stopping torque of said unit.

7. In apparatus of the character stated, a casing including a lower portion and an upper portion, a spring in the bottom of said lower portion, a motor compressor unit supported by said spring and enclosed by said casing, and means for resiliently connecting the upper part of said unit to the upper part of said lower casing portion for cushioning vibration of said unit and the starting and stopping torque of the motor

of said unit, said means being disposed above the upper edge of said lower casing portion and accessible upon removal of the upper portion of said casing.

8. The structure recited in claim 7 in which said means includes spaced plates carried by the upper part of said lower casing portion and extending into said upper casing portion, an arm carried by the upper part of said unit, with the lower end of said arm disposed between said plates, and horizontally disposed springs compressible tangentially of a circle concentric with the axis of rotation of the motor of said unit and engaging said plates and the opposite sides of the lower portion of said arm.

9. In apparatus of the character stated, a casing, a vertically disposed compression spring in the lower portion of said casing, a motor pump unit supported by said spring and having a casing, a pair of spaced vertically disposed plates carried by one of said casings, a horizontally disposed bolt passing through said plates, a vertically disposed arm, means for rigidly and adjustably securing said arm to the other of said casings, there being an aperture in an end portion of said arm through which said bolt passes, said aperture being larger than the thickness of said bolt, and oppositely disposed, horizontally compressible springs confined between said plates and the opposite sides of said end portion of said arm for yieldingly resisting the horizontal movement of said arm to absorb horizontal vibration and the starting and stopping torque of said motor pump unit.

10. A mounting for a vertical motor compressor unit in a casing unit including a tube connected rigidly at one end to said motor compressor unit and at the other end to said casing unit, said casing unit comprising an upper portion, a lower portion and a joint between said portions, said mounting comprising resilient means in said lower portion for supporting the weight of said motor compressor unit, a peg and ring engagement between the lower portion of said motor compressor unit and the lower portion of said

casing unit, said ring being secured horizontally to one of said units and said peg being secured vertically to the other of said units and located within said ring, said ring being spaced horizontally from said peg to allow the normal operating vibrations of said motor compressor unit to take place, said spacing however being sufficiently small to prevent a horizontal movement of the lower portion of said motor compressor unit tending to injure the above-described structure, a support secured to the lower portion of the casing unit and extending into the upper portion thereof, resilient means connected to said support and to said motor compressor unit for absorbing the vibrations thereof, and a lost motion connection between said support and said motor compressor unit which permits the normal vibrations thereof to take place but prevents a movement thereof sufficient to injure any of the above-named parts and also prevents disengagement of said peg from said ring, said last-named resilient means and said lost motion connection being detachable from the support and lying in the upper portion of said casing unit.

11. The structure defined in claim 10 including means for adjustably varying the securement of said last-named resilient means and lost motion connection to said motor compressor unit on a vertical plane.
